[57] CLAIM

The ornamental design for a "Flourescent lamp fixture," as shown and described.

DESCRIPTION

FIG. 1 is a perspective view of the fluorescent lamp fixture of this invention showing the top and right side end.

FIG. 2 is a perspective view of the lamp fixture of FIG. 1 showing the bottom of the fixture from the right side end.

FIG. 3 is a top plan view of the fixture of FIG. 1.

FIG. 4 is a side elevational view of the fixture of FIG. 1 and of the opposite side view being the same.

FIG. 5 is a bottom plan view of the fixture of FIG. 1; and;

FIG. 6 is an end side view of the fixture of FIG. 1 on a reduced scale, the opposite end side view being the same.
